UNITED STATES PATENT OFFICE.

BENJAMIN L. PHILLIPS, OF PROVIDENCE, RHODE ISLAND.

IMPROVEMENT IN PANTOGRAPHIC-ENGRAVING MACHINES.

Specification forming part of Letters Patent No. 37,177, dated December 16, 1862.

To all whom it may concern:

Be it known that I, BENJAMIN L. PHILLIPS, of the city and county of Providence, and State of Rhode Island, have invented Improvements in Pantographic-Engraving Machines, of which the following is a full, clear, and exact description, reference being had to the accompanying drawings, making part of this specification, in which—

Figure 1 is a perspective view of my improved machine for engraving copper cylinders; Fig. 2, a transverse vertical section through the middle of the machine; Figs. 3, 4, 5, 6, details to be referred to hereinafter.

My present invention consists in certain improvements in pantographic-engraving machines, which are more particularly used for engraving or tracing designs on cylinders for the use of printers on calico and other fabrics.

That others skilled in the art may understand and use my invention, I will proceed to describe the manner in which I have carried out the same.

In the said drawings, A is the frame of the machine; B, a heavy beam, which extends lengthwise of the machine and supports the cylinder C, which is to be engraved, and also the frame-work which carries the diamond or graver. D is the table on which the design or pattern to be copied is placed. The tracer-point *a*, with which the operator follows the pattern, is attached to the outer end of an arm or tongue, *b*, extending from a carriage, E, which traverses lengthwise of the machine on a rail, *c*, attached to a bar, F, (grooved wheels *d* on the carriage running on this rail.) A plate or hook, *e*, attached to this carriage, is bent under the bar F and prevents the carriage from being thrown off from the rail. Another carriage, G, runs on a rail on the beam H, and is held from being thrown off the rail by a hooked plate, *f*. A tongue, *g*, attached to this latter carriage, projects toward the table D, and rests in a grooved block, *i*, on top of the carriage E. This permits the lower carriage, E, to be moved toward and from the table D independently of the carriage G, but when the tracer-point *a* is moved lengthwise of the table D, the two carriages are moved together along their rails. The bar F is attached at either end to a rail, *l*, which rests near one end on a grooved pulley, *h*, in a hanger, *k*, and is connected at its

other end to the top of a segment, K, the edge of which lies in a groove, 3, in the bottom of the rail. Two wires, 4, are fastened one to each corner of the segment K and to the rail I, so that as the rails are moved back and forth (by the movement of the tracer-point *a*) the segments will revolve a shaft, L, to which they are attached, and this, through the arms M, connecting-rods *l*, and arms N, revolves two short shafts, O, which have their bearings in studs *m* on top of the beam B. The arms N are fastened to the shafts O by thumb-screws 5, so that the shafts may be turned around into a different position and the arms again be secured by tightening these screws. Each shaft O carries a roller, *p*, the face of which is roughened. The cylinder C rests on these rollers *p* and on another pair, *o*, and is revolved by the friction of the rollers *p* on its surface. By the above connections the movement of the tracer-point *a* across the table D gives a partial revolution to the cylinder C. The movements of the tracer lengthwise of the table and of the carriages E and G along their rails are communicated to the graver-carriage in the following manner: This carriage, on which one or more diamonds or gravers, *r*, are carried, is formed of two longitudinal pieces, P and Q, held together by cross-braces *s*. It rests on wheels *t* *u*, attached to brackets R on each side of the beam B, to which the brackets are secured by screws 6, passing through slots, which allow the brackets to be raised or lowered. The wheels *t*, on which the piece P rests, are flat on the face, but the other pair, *u*, have a rounded edge, and run in a groove, 7, in the lower side of the piece Q, to guide the movements of the carriage. A second groove, 8, inclined to the other one, as shown in Fig. 3, is made to receive these wheels, *u*, when the carriage is required to move in a line inclined to the axis of the cylinder C. Inclined ways S rise one from each end of the two pieces P and Q, and are joined in pairs, as shown in the drawings. They each have a slot, *v*, through which passes a screw, 9, which enters a bar, T. This permits the bar to be adjusted in different positions, higher up or lower down, on the ways. There are two of the bars, one on each side of the cylinder C. A bar, U, (shown detached in Fig. 4,) is pivoted at 10 to a projecting stud, 11, on the piece Q. It also has a pin or screw, 12, which passes through a slot in one

of the cross-braces s . This is necessary to allow the carriage to be inclined. A joint, 13, is necessary when the carriage is raised or lowered. Two strips, v' , of metal, are attached at 14 to this bar U , and are wound in opposite directions round the head w of a vertical shaft, V , and are attached thereto. This shaft has its bearings in suitable brackets, and carries near its lower end a grooved pulley, W , around which two or three turns of a brass wire, x , are taken. The wire then passes round another pulley, of the same size, at the opposite end of the machine, and back to the pulley W . Two small clamps, a' a^2 , which are closed by screws, are attached to the tongue g of the carriage G . The wire x is placed in one or the other of these clamps, and its screw is tightened up. Thus the motions of the carriage G revolve the shaft V , and through the bar U move the graver-carriage, the motion of this carriage being in the same direction as that of the carriage G when the wire is attached to the clamp a^2 , and in the contrary direction when it is released from this clamp and is caught in the other one.

The above-described mechanisms or methods of communicating the motions of the tracer-point a to the cylinder C , to revolve it beneath the graver, and to the graver carriage to move the graver over the cylinder, I consider greatly superior to those employed in any other machine of this class with which I am acquainted, the connections being such that there is no lost motion or slip, which is so frequently the cause of the marks on the cylinder not corresponding nicely with the pattern traced.

The inclined groove S , on the under side of the piece Q of the graver-carriage, enables the operator, by inclining the path of this carriage to the axis of the cylinder C , to slash his work, or to incline the lines marked on the cylinder at an angle to those on the pattern. This is sufficient when one graver only is used, but when a series of them is employed, a further change becomes necessary to make them all accord in the paths which they follow. This is done by changing the position of the bar F , on which the tracer-carriage E runs. It has a slot, b^2 , at one end, which permits it to be inclined to the rails I . This produces the desired result without inclining the pattern to the base-line from which the operator works. The graver r is attached to an arm, c^2 , which is pivoted at 20 to a plate, d^2 , attached to the top of the bar T . The short shaft 20, to which the arm c^2 is attached, also carries a cogged segment, e^2 , with which engages another cogged segment, f^2 , pivoted on a short standard, 21, rising from the plate d^2 . An arm, g^2 , which carries a weight, h^2 , (which may be adjusted on the arm,) is attached to a plate, i^2 , also pivoted on the standard 21. A set-screw passes through a curved slot in the segment f^2 and screws into the plate i^2 , by which the positions of the plate and segment with respect to each other may be varied to keep the arm g^2 horizontal. The toothed faces of the

segments e^2 and f^2 are eccentric to their pivots. This eccentricity compensates for changes in the relative positions of the graver-arm c^2 and the weighted arm g^2 , it being desirable to keep the latter arm as near level as possible, while the position of the graver and the inclination of its arm c^2 is frequently changed as the graver is worked on different parts of the cylinder C , or on different-sized cylinders, it being obvious that without some compensation the weight of the graver-arm and head would not influence so much the operation of the graver when the arm approached a vertical plane passing through its pivot 20 as it would when near a horizontal position. When the position of the graver-arm c^2 is changed, the set-screw which holds the segment f^2 and plate i^2 together is loosened, and when the arm has been adjusted it is again tightened up. The weighted arm g^2 rests on the edge of a bar, k^2 , which is pivoted eccentrically to two lugs, l^2 , projecting one from each end of the bar T . By rotating this bar k^2 a short distance, the weight h^2 is lowered and presses the graver down onto the cylinder C . The bar k^2 is operated from a treadle, A^2 , through a system of levers and connecting rods, 23, 24, 25, 26, 27, 28, 29, 30, and 31, the bars on both sides of the cylinder being operated at the same time when two sets of graters are in use. A spring, B^2 , draws the lever 23 down when the foot is raised from the treadle. The position of the graver r , with respect to the cylinder C , or the part of the circumference of the cylinder on which it is to operate, either on top, as here shown, or farther down the side, is adjusted by moving the bar T up or down on the inclined ways S , and also by raising or lowering the graver-carriage, by loosening the screws 6, which hold the brackets R , and moving the brackets, care being taken to keep the graver pointed toward the axis of the cylinder. The ways S being straight, the bar T may be moved without changing its level and without affecting the horizontal position of the weighted arm g^2 , which I consider a great advantage over the curved or segmental ways or bars heretofore used. Having the weighted arm g^2 hung on a separate pivot from that on which the graver-arm c^2 vibrates permits the adjustment of the latter arm without disturbing the position of the weight, as before described. The "grounding," as it is termed, or filling in portions of the design with lines drawn parallel to each other, and generally inclined at a certain angle to the pattern, constitutes a considerable portion of the labor of copying. To facilitate this work I connect the two carriages F and G by bands or wires passing round pulleys of different diameters, so that as the operator moves the tracer-point a across the pattern these two carriages will assume such a relative speed, one to the other, that a line at the required angle will be produced on the cylinder C ; and in connection with this I have arranged an automatic feed, which places these lines at an equal and re-

quired distance apart. A vertical shaft, D^2 , has its bearings in the frame A, and carries a grooved pulley, E^2 , which is loose on the shaft, and one of less diameter, G^2 , the relative size of these pulleys governing the angle at which the grounding-lines will be drawn. A wire, n^2 , is attached to the pulley E^2 , and after making two or three turns around it passes over another pulley, F^2 , of same diameter, at the opposite end of the machine, and back to the pulley E^2 , to which it is fastened. A screw-clamp, o^2 , on the carriage G, is made to hold this wire when this mechanism is to be brought into use; at other times it is left free. A wire, r^2 , (shown dotted in Fig. 2,) attached to the outer end of one of the rails I, is passed round the smaller pulley, G^2 , and is again fastened to the rail. From this connection the movements of the carriage G along the beam H communicate a transverse motion to the carriage E, but at a slower rate, and a diagonal line is drawn upon the cylinder C, the operator not being compelled to guide the tracer-point, but only to move it across the pattern. The lower pulley, G^2 , is secured to the shaft D^2 by a set-screw, p^2 , which may be loosened and the pulley revolve without the shaft, so as not to interfere with the movements of the rail I when the grounding or lining device is not being employed. A disk, H^2 , notched around its periphery, as shown detached in Fig. 5, is secured to the shaft D^2 . Two pawls, s^2 u^2 , are pivoted to the top of the pulley E^2 , and are held in contact with the edge of the disk by a spring, v^2 . An arm, I^2 , is attached to the shaft D^2 by being pressed down onto a shoulder by a friction-nut, v^2 , which screws onto the head of the shaft and presses the head of an arm, m^2 , attached to the frame A, onto the arm I^2 , and prevents this arm from being carried round with the shaft, except when it is moved by two pins, 3, which rise from the pulley E^2 . This arm I^2 has a cam, w^2 , formed on it, which lifts the pawl s^2 as the pulley E^2 is revolved in the direction of the arrow 4 by the movement of the carriage G in the direction of the arrow 6, Fig. 1, and holds this pawl clear of the disk until the return-movement of the carriage carries the pulley back far enough for the pawl u^2 to drop in the next notch. Thus the pulley E^2 is permitted to slip round on the shaft D^2 at each traverse of the carriage G an amount equal to the space between the notches on the disk, without moving the pulley G^2 or the carriage E, consequently the next forward movement of the carriage G will make the next line at a short distance from and parallel with the last. To change the spaces between the lines, the disk H may be changed or the pins 3 may be moved to allow the pawls to take two notches at a time. Another part of the labor of tracing which I propose to economize is where the same figure—such as a leaf or circle—occurs frequently in the pattern, I employ a templet, of sheet-zinc or other suitable material, which I lay on the

pattern in line with the figure which has just been copied, and with a supplementary tracing-point, a^3 , on an arm, b^3 , which extends across the end of the tongue b , I follow the outline of the templet much more rapidly than the figure could be again traced from the pattern with the tracer-point a .

I am aware of the Letters Patent granted to John and Thomas Hope, assignees of John Hope, dated March 9, 1858, in which a supplementary wedge-shaped tracer-point was guided in grooves cut in a board to assist the copyist in grounding his figures; but my idea goes further in enabling him to copy the outlines rapidly or to repeat the figures. I am also aware that templets have been used with the single or main tracer-point a , the templet being placed immediately over the figure on the pattern, which prevented the operator from seeing his pattern and from detecting and correcting errors by watching his pattern, as my arrangement enables him to do. To facilitate arranging the templets in line with the same figure on the pattern, I have a point to designate the center of the figure, and when the tracer-point a is placed on the center of the figure in the pattern or on the mark made by the templet where last laid down, and the other point, a^3 , is placed on the center of the templet, I know that it is in line with the last figure made. The handle c^3 bears and moves upon the table or pattern and serves to steady the arm. The tracer-point a is also adjusted to bear upon the table, and has its point rounded to prevent its catching in the pattern. The several pulleys to which the wire or bands are attached—such as W E^2 G^2 —are, as before stated, cut with inclined grooves, like a fine screw-thread, for the wires to lie in. This I consider essential when several turns of the wire are passed round the pulley to prevent one turn of the wire riding over another, and I take these several turns, as by so doing I can reduce the size of the pulley and still have length enough of wire to allow the traverse of the carriage, to which it may be connected for the whole length of the machine.

The operation of this machine is as follows: The pattern to be traced onto the cylinder C is secured to the table D, and the operator follows the lines of the pattern with the tracer-point a . All the lines and curves which the tracer point may pass over are embraced within two movements or lines at right angles to each other on the table. One of these movements of the tracer-point—viz., back and forth across the table, or in line with the tongue b —revolves the cylinder C on its axis through the following connections: As the carriage E is moved toward and from the table D it carries with it the bar F and rails I. These bars being connected by the wires 4 to the segments K, the shaft L is revolved a part turn in one direction or the other. The arms M, attached to the shaft L, are connected by the rods l with the arms N, secured to the short shafts O,

and the movements of the shaft L are thus transmitted to these shafts, which carry the friction-rollers p on which the roll C rests. The movements of the tracer-point lengthwise of the table or across the front of the machine cause the carriage G to move along on its rail on the beam H, (the carriage E being connected, of course, follows it.) The wire x being attached to the tongue of the carriage either at a' or at a², (according as it is desired to have the graver move in the same direction with the tracer or counter to it,) the pulley W is revolved, and through the attachment of the bands v' on the head of the shaft V and the bar U the graver-carriage is moved longitudinally along the cylinder C, the graver r tracing lines which accord with those on the pattern on the table D.

When the parts are in the position shown in Fig. 2, the graver-point r is raised from the surface of the cylinder C, but when the operator commences to trace the pattern he presses his foot on the treadle A², when, through the connections 23, 24, 25, 26, 27, 28, 29, 30, and 31, the eccentric-rod k² is turned down, which lowers the weight h², revolves the cog-segments f² e², and lowers the graver-point r onto the cylinder. When it is desired to "slash" the work or to give to the lines produced by the graver-point a different inclination from those on the pattern, the graver-carriage is lifted up and the wheel u is entered in the inclined groove 8 in the bar Q of this carriage; or when a series of graver-points are in use, and they all have to accord in their movements, the bar F, on which the tracer-carriage E runs, is inclined by moving one end of it along on one of the rails I, the screw and slot b² permitting this. When it is required to change the position of the graver-point r higher or lower on the cylinder C, or to suit a cylinder of greater or less diameter, the bar T is raised or lowered on the inclined ways S, and the whole graver-frame is raised or lowered by moving the brackets R.

As before stated, the relative speed of the two carriages, G and E, the former along its beam H, and the latter toward and from the said beam, is changed to produce the inclined lines for ground-work, by connecting the carriage G at o² to the wire n² over the large pulley H² and by connecting the rail I, which is moved by the carriage E, to a pulley, G², of a different diameter, and these two carriages, controlling, as they do, the revolutions of the cylinder C and the traverse of the graver-carriage, will, by thus changing the speed of the graver-carriage relative to the speed with which the cylinder C is revolved, cause the

graver r to produce a line on the cylinder at a different inclination from the line followed by the tracer-point. For example, if the tracer-point a is moved in a straight line across the table D, moving the carriage E toward or from the table, the carriage G will move along the beam H at a different rate, proportionate to the different diameters of the two pulleys, G² H², and the graver-carriage will move along over the cylinder C at a different rate from that at which the cylinder is revolved.

The manner of using the supplementary tracing-point a³ has been fully explained, as well as the automatic feed connected with the pulley H².

What I claim as my invention, and desire to secure by Letters Patent, is—

1. The method of communicating the motions of the tracer-point a and carriage E to the cylinder C, substantially as described.
2. Supporting the bars T on fixed inclined ways S, substantially as and for the purpose set forth.
3. A compensating connection between the weighted arm g² and graver-arm c², substantially as described.
4. Pivoting the weighted arm g² at a different point from that at which the graver-arm c² is pivoted, that they may be moved separately, substantially as described.
5. The inclined groove 8, for guiding the graver-carriage, substantially as described.
6. Inclining the bar F, for the purpose specified.
7. Changing the relative speed with which the cylinder C is revolved and the graver-carriage is moved along the cylinder, by connecting the carriages E and G with pulleys of different size, substantially in the manner and for the purpose set forth.
8. The automatic feed connected with the pulley E² for regulating the spaces between the grounding-lines, substantially as described.
9. The employment of screw-scored pulleys, such as W E² G², on a pantographic-engraving machine, for the purpose specified.
10. The employment of templets cut out to the form of any figure which is to be repeated, in combination with a supplementary tracing-point, a³, to be used substantially as set forth.
11. Reversing the motions of the graver-carriage by clamping the wire 4 to the carriage G, either at a' or at a².
